(57) **CLAIM**

The ornamental design for a handle structure for a portable power station, as shown and described.

DESCRIPTION

FIG. 1 is a perspective view of a handle structure for a portable power station showing our new design;

FIG. 2 is a perspective view of a handle structure for a portable power station showing our new design;

FIG. 3 is a front elevational view of the handle structure for a portable power station seen in FIG. 1;

FIG. 4 is a rear elevational view of the handle structure for a portable power station seen in FIG. 1;

FIG. 5 is a right side elevational view of the handle structure for a portable power station seen in FIG. 1;

FIG. 6 is a left side elevational view of the handle structure for a portable power station seen in FIG. 1;

FIG. 7 is a top plan view of the handle structure for a portable power station seen in FIG. 1; and,

FIG. 8 is a bottom plan view of the handle structure for a portable power station seen in FIG. 1.

In the drawings, the broken lines depict portions of the handle structure for a portable power station that form no part of the claimed design.
